LIQUID DISPLACEMENT GAS COMPRESSOR

Filed Dec. 14, 1931

UNITED STATES PATENT OFFICE

DONALD G. GRISWOLD, OF LOS ANGELES, CALIFORNIA

LIQUID DISPLACEMENT GAS COMPRESSOR

Application filed December 14, 1931. Serial No. 580,869.

This invention has to do with gas compressors, and is more particularly related to gas compressors of the so-called liquid displacement type in which the compressing action is derived through the displacement of the gas in a suitable chamber by liquid under pressure.

The gas compressor contemplated by this invention is especially adapted for use in maintaining a substantial air pocket in the upper portion of water supply reservoirs such as are employed in connection with individual domestic water softening units. The invention is not, however, confined to this particular use, but may find application in compressing air or other gas where there is a source of liquid supply commensurate with the pressure to be obtained in the compressed medium.

I am aware of the fact that attempts have been made to produce gas compressors of the general character referred to above. So far as I am aware the general construction employed in these prior attempts comprises a shell forming a compressing chamber. This shell is provided with a gas inlet and a gas outlet and with a liquid inlet and a liquid outlet. The liquid inlet and outlet are provided with valve means associated with a float mechanism, the valve being arranged so as to be operated directly from the float. In other words as the float rises to a predetermined point in the chamber the inlet valve is closed and the outlet valve is opened permitting the liquid to flow out of the chamber, thus lowering the float to a predetermined low point at which the outlet valve is closed and the inlet valve is opened.

Most of the attempts to produce a gas compressor embodying the construction outlined above have failed due to the fact that where the valves are operated directly from the float there is what may be termed a dead center at which both the inlet and the outlet ports are open, thus permitting the free circulation of liquid through the chamber without any displacement action.

Furthermore, in these prior devices where a single float is employed for controlling the valves there is always a certain amount of

compressed gas in the upper portion of the chamber when the float reaches its maximum level. In a construction of this nature it will be seen that this compressed gas must expand until a pressure below atmospheric is obtained in the chamber before any free gas can be drawn into the chamber through the air inlet. In an effort to obviate this expansion of compressed gas certain attempts have been made to provide auxiliary air outlets which are open when the float reaches its maximum level for the purpose of permitting this compressed gas to exhaust into the atmosphere. It will be seen that in constructions of this nature whether the device is provided with an auxiliary gas outlet or not, there is a substantial loss in efficiency due to the compressed gas in the compression chamber when the liquid reaches its maximum level. It therefore becomes one object of my invention to produce a liquid displacement gas compressor which is so constructed that the compressing chamber is completely filled with liquid when the inlet valve is closed and the outlet valve is opened. Pursuant to the attainment of this object I provide the compressing unit with two chambers, one of which I may term a main compressing chamber and the other an auxiliary or gas outlet chamber. A check valve is provided between these two chambers to permit the flow of air from the main chamber into the gas outlet chamber which is connected to the vessel into which the compressed gas is to be delivered.

It is a further object of this invention to provide a valve actuating mechanism which may be broadly described as operating independently of the floats in the compressor. The valve actuating mechanism does not operate independently of the floats in that there is no relation between the floats and this mechanism, but the relation is an indirect one. In other words, the actual mechanism which operates the valve is merely controlled by the floats, the valves themselves being operated by an independent mechanism. In this way I positively avoid the possibility of having a so-called dead center at any time in the operation of the compressor, where the two

valves may be closed or both valves may be partly open which would permit free circulation of liquid through the chamber.

It is a further important feature of this invention that the valve operating mechanism is so constructed that the open valve closes before the closed valve is open, regardless of which valve is open. This also is important in avoiding the possibility of having 10 the so-called dead center.

The details in the construction of a preferred form of my invention, together with other objects attending its production, will be best understood from the following description 15 of the accompanying drawing which is chosen for illustrative purposes only, and in which—

Fig. 1 is an elevational view partly in section and partly broken away illustrating one 20 preferred application of the device contemplated by this invention;

Fig. 2 is an enlarged sectional elevation showing the details in the construction of a preferred form of my invention;

Fig. 3 is a plan section taken in a plane represented by the line 3—3 in Fig. 2;

Fig. 4 is a fragmentary sectional view which shows the operation of a latch mechanism designed for use in connection with my 30 invention;

Fig. 5 is a sectional elevation showing the details in the construction of a preferred form of valve mechanism adapted for use in my invention;

Fig. 6 is a sectional view taken in a plane 35 represented by the line 6—6 in Fig. 5;

Fig. 7 is a sectional view taken in a plane represented by the line 7—7 in Fig. 5;

Fig. 8 is a sectional view taken in a plane 40 represented by the line 8—8 in Fig. 7;

Figs. 9 and 9A are end elevations of the valve core looking in the direction of the arrow 7—7 and showing the manner in which this valve mechanism operates.

More particularly describing the invention as herein illustrated, reference numeral 11 indicates a storage tank which may be of the type ordinarily used in connection with domestic water softeners and it is well known 45 that in tanks of this nature the operativeness of such tanks is dependent upon the maintenance of an air space in the upper end portion of the tank, and due to leaks and other means of losing air in tanks of this nature 50 it is customary to provide a pump or compressor of some nature to maintain this space filled with air under pressure.

As pointed out above the device contemplated by this invention is especially designed 60 to automatically maintain a predetermined quantity of air in the upper end portion of tanks of this nature and in Fig. 1 I show at 11a a preferred form of automatic air compressor of the type contemplated by this invention. This compressing unit comprises

a housing 12 provided with an air inlet 13, an air outlet 14 leading to the upper end portion of the tank 11, a liquid inlet 15 which is shown as being connected to an intermediate portion of the tank 11 below the liquid level therein, and a liquid outlet 16. It will be understood, of course, that the compressor contemplated by this invention is not necessarily confined to the particular application shown in Figure 1, but the air outlet may be connected to any suitable compressed air or compressed gas reservoir and the water or liquid inlet 15 may be connected to any suitable source of liquid supply such as a water main.

The details in the construction of the compressor contemplated by this invention are best illustrated in Figs. 2 to 9A inclusive. Referring to Figure 2, it will be observed that the housing 12 is divided into a main compressing chamber 18 and a gas outlet chamber 19 by a partition member 20. For convenience in construction, the chambers 18 and 19 may be formed in two separate units connected together by the flange connection indicated at 21 and the partition plate 20 may be interposed between the two flanges in the adjacent sections.

The partition member 20 is provided with a check valve 22 adapted to permit the unidirectional flow of air from the main compressing chamber into the gas outlet chamber and the air inlet 13 is necessarily provided with a check valve of any suitable type such as is indicated by reference numeral 23.

As a further convenience in the construction of this unit the water inlet and outlet 15 and 16 respectively may be connected to a special inlet fitting 24 which in turn is connected to the central section of the housing through a flange connection 25 which has formed therein an inlet nose or chamber 26 provided with an opening 27 which receives a valve seat 28 upon which an inlet valve 29 is adapted to seat. The outlet pipe 16 is connected to a nipple 31 mounted in a suitable opening in the bottom of the flange 24, such nipple having a seat provided at its upper end adapted to receive an outlet valve 32. Both the inlet valve and the outlet valve are shown as being provided with guide stems 33, 34, 35 and 36 on their upper and lower ends respectively.

For the purpose of mechanically operating these two valves I connect the lower stem 35 on the inlet valve and the upper stem 34 on the outlet valve to a lever member 40 by means of pivot pins 41 and 42, respectively. It will be noted that the lever member 40 is connected at one end portion to the stem 35, at an intermediate portion to the stem 34 and at its other end portion it is connected to an operating link 41 which has its upper end pivotally connected to a link operating lever 42. Such lever 42 is pivoted in a notch 43 of a suitable housing 44 which is shown as

being mounted upon or formed with a diaphragm housing 45.

The diaphragm housing 45 contains a flexible diaphragm 46 which is secured at its mid portion 5 to a reciprocable shaft or rod 47 extending through a spring compressed packing gland 48 into the housing 44. The upper end portion of this rod or shaft 47 projects into a guide pocket 50 formed in the lower end portion of standard 51 which is secured at its lower end to the housing 44. At an intermediate point on the rod 47 I provide lever engaging means such as a pair of flanges or bosses indicated by reference numerals 52 and 53. These flanges extend over opposite sides of the inner end portion of the lever 42.

It will be seen from the construction so far described that when the rod or shaft 47 is drawn downwardly by the action of the diaphragm 46 the outer end of lever 42 will swing upwardly in the direction of the arrow A, carrying with it the link 41 which moves about its fulcrum on the stem 34 to close the inlet valve 29. The continued movement of this lever then opens the outlet valve 32 and permits the liquid in the main compressing chamber to drain. The opposite movement of the diaphragm, assuming the parts just referred to be in a position wherein the inlet valve is closed and the outlet valve is open, swings the lever 42 in the opposite direction so that the lever 40, which now has its fulcrum on the valve stem 35, is effective to close the outlet valve 34 and open the inlet valve 35. Thus it will be seen that there is no possibility of having a dead center of a relative position of the valves in which both of them are open.

The diaphragm 46 is of course adapted to be operated by the action of a pressure fluid on one or the other sides of the diaphragm. Reference numeral 60 indicates a connection for delivering pressure fluid to the upper side 45 of the diaphragm housing and reference numeral 61 indicates a connection for delivering pressure fluid to the lower side of the diaphragm housing. The connections 60 and 61 lead to a four-way valve mechanism 62 which has an inlet 63 connected to the main liquid inlet chamber 26 or to any other suitable source of pressure fluid supply and an outlet connection 64 which is shown as being connected to the outlet nipple 37.

With regard to the four-way valve mechanism it will be understood that when one of the connections 60 or 61 is acting as an inlet for its associated side of the housing, the other conduit acts as an outlet for its corresponding side of the housing, and vice versa, so that when pressure fluid is being delivered through connection 60 into the upper side of the housing, the pressure fluid in the lower side of the housing is being forced out through the connection 61. It will be seen,

therefore, that the opening and closing of the respective inlet and outlet valves 29 and 32 is indirectly controlled by the operation of the four-way valve 62.

In order to accomplish the operation of this last mentioned valve automatically with the filling and emptying of the main compressing chamber, I propose to operate the four-way valve by a float mechanism which in turn is actuated by the movement of the liquid in the main compressing chamber.

This so-called float mechanism is shown as comprising a link 70 which is pivotally attached at its lower end to a valve operating lever 71. (See Fig. 5.) The upper end of the link 70 is attached to an arm 72 which is secured to a flange 73 on the lower end of a sleeve 74 which is slidably mounted on the standard 51. The upper end of the sleeve 74 is provided with a cup member 75 which forms an outer shoulder 76 and an inner shoulder 77. When the sleeve is in its lowermost position it is held against upward movement relative to the standard 51 by a latch mechanism which is shown as comprising a pair of balls 78 and 78' positioned in suitable apertures formed on the upper end portion of the standard and forced into the cup 75 so as to be engaged by the shoulder 77 by a pin 80.

A float 81 is slidably mounted on the sleeve 74 and the upper outlet chamber 19 is provided with a latch actuating float 82 which has a seat portion 83 adapted to set in a fitting 84. This float has on its upper end a guide pin 85 adapted to be received in a fixed sleeve 86 in the top of the outlet chamber and the lower end of the float is attached through the medium of a pin 87 and a flexible connection such as a chain 88, with the upper end of the pin 80. Assuming the parts to be in the position shown, it will be seen that liquid such as water under pressure is entering the main compressing chamber through the valve 29. As this liquid rises in the chamber the float 81 is forced upwardly into engagement with the shoulder 26. The latch mechanism, however, holds the sleeve and the float against further movement and the liquid continues to rise at the same time forcing the air in the main compressing chamber into the outlet chamber through the check valve 22. The flow of liquid continues until the liquid has completely displaced the air or gas in the main compressing chamber 18 and enters the outlet chamber 19 through the check valve 22 and the valve 83 on the lower end of the latch control float. As the liquid rises in the outlet chamber the float 82 is raised from the position shown, such upward movement being effective to lift the pin 80 upwardly to a position at which the balls 78 and 78' may move inwardly into the transverse passage 77' in the standard, as shown in Fig. 4. This inward movement of the balls permits the

float 81 to move downwardly into the lower position shown in Fig. 5, thereby closing the valve 29 and opening the valve 32. The float 81 is held in this position by the latch mechanism, which holds the sleeve 74 against downward movement. The liquid continues to flow through the outlet chamber 19 until the liquid has completely displaced the air or gas in the outlet chamber 19 and enters the main compressing chamber 18 through the valve 32 and the valve 83 on the lower end of the latch control float. As the liquid rises in the main compressing chamber the float 81 is raised from the position shown, such upward movement being effective to lift the pin 80 upwardly to a position at which the balls 78 and 78' may move inwardly into the transverse passage 77' in the standard, as shown in Fig. 4. This inward movement of the balls permits the

float 81 to lift the sleeve 74 upwardly. The upward movement of the sleeve operates the four-way valve so that pressure fluid is admitted to the upper side of the diaphragm 5 housing and exhausted from the lower side of such housing, permitting the diaphragm to move downwardly and close the inlet valve and open the outlet valve in the manner heretofore described.

10 When the positions of the inlet and outlet valves are reversed the liquid in the main compressing chamber 18 flows outwardly and is displaced with atmospheric air which enters the main compressing chamber through 15 the check valve 23. As the liquid level recedes the float of course lowers and eventually engages the flange 73, the weight of the float being effective to move the sleeves and the arms 72 downwardly, thereby acting 20 through the link 70 to reverse the position of the four-way valve so that the positions of the valves 29 and 32 are again restored to that shown in Fig. 2 and the operation is reversed.

In a device of the character shown in Fig. 25 1 the operation just described continues automatically until the liquid level in the main tank 11 has been forced downwardly to the level of the upper latch control float 82.

It will be understood that in a device of 30 this character the four-way valve 62 may be of any conventional type which can conveniently be arranged for operation with the other mechanism. In order to avoid difficulties in operation due to faulty operation of 35 this valve, and further to provide a valve mechanism which occupies a minimum of space and is rapid and positive in operation, I have developed a four-way valve, the details in the construction of which are best illustrated in Figs. 5 to 9A inclusive. This valve is shown as comprising a main housing 90 which is connected with the pressure fluid inlet 63 and has inlet-outlet connections 60 and 61 which are adapted to be connected with the 40 top and bottom portions of the diaphragm housing 45. The connections 60, 61 and 64 all lead inwardly into individual ducts indicated at 91, 92 and 93 which extend in substantially parallel relation through the housing 45 to a flat bearing face 95 formed on an extending box 96. Reference numeral 97 indicates a valve core housing which is mounted on the main housing 90 by means of screws 98 and contains a valve core member 97a 50 which is mounted on an operating pin 98 and is held in sliding engagement with the bearing face 95 by a spring 99 which engages a collar 100 which is keyed to the stem 98. The outer end of the stem 98 is keyed to the 55 operating lever 71 referred to above.

The valve core member is provided with a U-shaped passage 102 which has two outlets 103 and 104, the outlet 103 always being in registration with the duct 93 connected with the outlet passage 64 and the other opening

104 being adapted upon rotation of the plug to register alternately with the ducts 91 and 92, as indicated in Figs. 9 and 9A. In addition to the U-shaped passage the core member 97 is provided with a pair of spaced passages 105 and 106 each angularly spaced an equal distance away from the opening 104. These passages extend clear through the core member into the portion of the fitting 97 below the core member which is provided with a pressure fluid inlet 108.

From Figure 9 it will be seen that when the two openings 103 and 104 in the U-shaped duct are connected with the ducts 91 and 93 respectively, that the passage 106 is in register with the duct 92 and the passage 105 is of course closed. With the valve in this position pressure fluid is flowing through passage 103, duct 92 and pipe 61 into the lower side of the diaphragm housing 45, at the same time fluid is being exhausted from the diaphragm housing through pipe 60 into duct 92 from which it passes into opening 104 through the U-shaped duct out through opening 103 into duct 93 through which it enters the outlet passage 64.

When the valve core is rotated in the direction of the arrow B by the shaft 98 and its associated lever 71 to the position shown in Fig. 9A, the outlet duct 64 is connected with the diaphragm connection 61 through the U-shaped passage and the duct 91 which leads to connection 60 is connected with the inlet pipe 63 through the passage 105. This last named position is the position from which pressure fluid will be delivered into the housing so as to bring about the closing of the main liquid inlet valve and the opening of the main liquid outlet valve 29 and 32, respectively. As a means for lubricating the bearing faces between the valve core and the boss on the housing, the boss 110 is received as indicated at 110 and the valve core is provided with a passage 111 corresponding in shape to the recess and adapted to carry pressure fluid into engagement with a lubricating grease contained in the recess and passage. As pointed out above, various types of four-way valves may be used to control the delivery of pressure fluid to the outside diaphragm housing. I find, however, that the valve just described has certain advantages in that it is quick and positive in its operation, it requires a very small movement to effect its operation, and it is small and compact so that it occupies a minimum space in the compressing chamber.

It will be apparent from the foregoing description that the compressor contemplated by this invention is so designed that there is a complete displacement of the air in the main compressing chamber, consequently there is no loss in efficiency due to the expansion of this air as the liquid in the main compressing chamber recedes or due to the ex-

- haustion of this air in order to avoid its expansion. Furthermore, it will be observed that the valve mechanism is actuated by means which operate independently of the 5 floats, the floats being provided solely for the purpose of controlling the mechanism which actuates the valve. In other words there is an indirect action here which positively prevents the occurrence of any dead centers in 10 the valve mechanism. Furthermore, the means for operating the valves is arranged so that the open valve is always closed before the closed valve is open.
- It is to be understood that while I have 15 herein described and illustrated one preferred form of my invention, the invention is not confined to the precise construction described above, but includes within its scope whatever changes, modifications, or arrangements 20 that fairly come within the spirit of the appended claims.
- I claim as my invention:
1. A gas compressor of the class described embodying: a housing having a main compressing chamber and an auxiliary float and outlet chamber; a check valve between said chambers; a liquid inlet and a liquid outlet in said main compressing chamber; an air inlet in said main compressing chamber; valve means in said liquid inlet and said liquid outlet; and float means in said chambers for controlling the actuation of said liquid inlet and said outlet valves. 25
  2. A gas compressor of the class described embodying: a housing having a main compressing chamber and an auxiliary float and outlet chamber; a check valve between said chambers; a liquid inlet and a liquid outlet in said main compressing chamber; an air inlet in said main compressing chamber; valve means in said liquid inlet and said liquid outlet; valve operating means for closing the liquid inlet valve and opening the liquid outlet valve; and a float in said outlet 30 chamber for actuating said valve operating means.
  3. A gas compressor of the class described embodying: a housing having a main compressing chamber and an auxiliary outlet chamber; a check valve between said chambers; an air inlet in said main compressing chamber; a liquid inlet and a liquid outlet in said main compressing chamber; a valve in said liquid inlet; a valve in said liquid outlet; a pressure operated diaphragm for alternately opening and closing said liquid inlet and outlet valves; and float operated means for controlling the movement of said diaphragm. 35
  4. A gas compressor of the class described embodying: a housing having a main compressing chamber and an auxiliary outlet chamber; a check valve between said chambers; an air inlet in said main compressing chamber; a liquid inlet and a liquid outlet in said main compressing chamber; a valve in 40
- said liquid inlet; a valve in said liquid outlet; a pressure operated diaphragm for alternately opening and closing said liquid inlet and outlet valves; means for alternately delivering pressure fluid to opposite sides of said diaphragm; valve means for controlling the delivery of said pressure fluid; and a float actuated by the liquid in said housing for actuating said last mentioned valve means. 70
5. A gas compressor of the class described embodying: a housing having a main compressing chamber and an outlet chamber; a check valve between said chambers; an air inlet in said main compressing chamber; a liquid inlet and a liquid outlet in said main compressing chamber; a valve in said liquid inlet; a valve in said liquid outlet; means for actuating said valves so that one valve is closed when the other valve is open; a float in said main compressing chamber; means associated with said float for controlling said valve actuating means; latch means in said chamber for holding said float against upward movement; and a second float in said outlet chamber for releasing said latch means when liquid from said main chamber enters said outlet chamber. 75
6. A gas compressor of the class described embodying: a housing having a main compressing chamber and an outlet chamber; a check valve between said chambers; an air inlet in said main compressing chamber; a liquid inlet and a liquid outlet in said main compressing chamber; a valve in said liquid inlet; a valve in said liquid outlet; means for actuating said valves so that one valve is closed when the other valve is open; a standard in said main compressing chamber; a sleeve slidably mounted on said standard; latch means for holding said sleeve against movement on said standard; a float slidably mounted on said sleeve; stops on the ends of said sleeve adapted to be engaged by said float; a diaphragm housing; a diaphragm in said diaphragm housing; valve means for controlling the delivery of pressure fluid into opposite sides of said diaphragm housing; means attached to said sleeve for operating said last mentioned valve means; means actuated by said diaphragm for opening and closing the liquid inlet and outlet valves; a float in said outlet chamber; and means actuated by said last mentioned float for releasing said sleeve latching mechanism. 90
7. A gas compressor of the class described embodying: a housing having a main compressing chamber and a gas outlet chamber; a check valve between said chambers; a liquid outlet and a liquid inlet in said main chamber; valves in said liquid inlet and outlet; and means for actuating said valves so that one is open when the other is closed, said actuating means comprising means independent of the liquid in said chamber for moving said valves and float means in said 95
- 100
- 105
- 110
- 115
- 120
- 125
- 130

- chamber for controlling said valve moving means.
8. A gas compressor of the class described embodying: a housing having a gas inlet, 5 a gas outlet, a liquid inlet, and a liquid outlet; valves in said liquid inlet and outlet; and means for actuating said valves so that one is open when the other is closed, said valve actuating means comprising a diaphragm housing, a pressure operated diaphragm in said diaphragm housing, a diaphragm control valve for governing the flow of pressure fluid into opposite sides of said diaphragm housing, lever means operated by 10 said diaphragm for actuating said valves; and float means in said housing for operating said diaphragm control valve.
9. A gas compressor of the class described embodying: a housing having a gas inlet, a 20 gas outlet, a liquid inlet, and a liquid outlet; valves in said liquid inlet and outlet; and means for actuating said valves so that one is open when the other is closed, said valve actuating means comprising a diaphragm 25 housing, a pressure operated diaphragm in said diaphragm housing, a diaphragm control valve for governing the flow of pressure fluid into opposite sides of said diaphragm housing, lever means operated by said dia- 30 phragm for actuating said valves, a standard in said compressor housing, a float slidably mounted on said standard, latch means on said standard for limiting the upward movement of said float; means associated with 35 said float for operating said diaphragm control valve, and a latch control float in said chamber for releasing said float for upward movement when a predetermined quantity of liquid has entered said housing.
- 40 10. A gas compressor of the class described embodying: a housing having a gas inlet, a gas outlet, a liquid inlet and a liquid outlet; valves in said liquid inlet and outlet; pressure operated diaphragm means for 45 actuating said valves; a standard in said housing; a sleeve slidably mounted on said standard; a stop on the lower end of said sleeve; a cup formed on the upper end of said sleeve forming an outer shoulder and 50 an inner shoulder; a float slidably mounted on said sleeve and adapted to engage the shoulders thereon; dogs in the upper end of said standard; a pin slidably mounted in said standard for forcing said dogs into said 55 cup to hold said sleeve against movement on said standard; a pin actuating float in the top of said chamber connected to said pin for releasing said dogs; and means attached to said sleeve for controlling the de- 60 livery of pressure fluid to said diaphragm means.
11. A gas compressor of the class described embodying: a housing having a gas inlet and a gas outlet; a liquid inlet and a liquid 65 outlet in said housing; an inlet valve in said liquid inlet; an outlet valve in said liquid outlet; a stem on the bottom of said inlet valve; a stem on the top of said outlet valve; an operating link mechanism; a lever having one end portion pivoted to said operating link, and having its other end portion pivoted to said inlet valve stem and an intermediate portion pivoted to said outlet valve stem, a pressure diaphragm unit; means for operating said link mechanism from said pressure diaphragm; valve means for controlling the delivery of pressure fluid to opposite sides of said diaphragm; and a float for actuating said last mentioned valve means.
12. A gas compressor of the class described embodying: a housing having a main compressing chamber and an auxiliary float and outlet chamber; a check valve between said chambers; an air inlet in said main compressing chamber; a valve in said liquid inlet; a valve in said liquid outlet; valve operating means for closing the liquid inlet and opening the liquid outlet; and float means in said housing for controlling the valve actuating means so that the inlet is closed and the outlet is opened when the liquid enters the gas outlet chamber, said float means including a float in the gas outlet chamber.
- In testimony whereof, I have hereunto set 95 my hand at Los Angeles, California, this 24th day of November, 1931.
- DONALD G. GRISWOLD.
